UNITED STATES PATENT OFFICE.

ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

PAPER-SCREEN.

1,284,669.

Specification of Letters Patent. Patented Nov. 12, 1918.

Application filed January 4, 1917. Serial No. 140,486.

To all whom it may concern:

Be it known that I, ANTON J. HAUG, a citizen of the United States, and a resident of Nashua, county of Hillsborough, State of New Hampshire, (whose post-office address is % Improved Paper Machinery Company, Nashua, New Hampshire,) have invented an Improvement in Paper Screens, of which the following description, in connection with the accompanying drawings, is a specification, like characters on the drawings representing like parts.

This invention relates to frame construction for screens or the like and particularly screens used for paper manufacture, such for example as the type of screen known as a cylinder mold, although the principles of this invention are applicable to the construction of screens used for other purposes.

20 The invention is more particularly concerned with the construction of a cylindrical frame intended to serve as the support for the foraminous covering of the screen, one object being to construct a cylindrical frame 25 work in such form as to be relatively inexpensive, easily manufactured and assembled by unskilled labor, and easily repaired.

In the case of many screens and cylinder molds in use, the construction is such as to 30 require highly skilled labor in manufacturing and assembling, and also a large amount of machining and drilling, thereby rendering the screen expensive to construct. The constructions of many of these screens preclude 35 the use of cast iron as a material for the supporting grille or frame because of expense and weight, and many of these cylinders when assembled for a solid, integral frame unit which not only requires skilled 40 and expensive labor in building and assembling, and particularly are expensive to machine after assembling, but also require special machinery when repairs are required to be made.

45 The herein-described embodiment of my invention contemplates the employment of interchangeable sections, which may be individually accurately machined and drilled and then assembled by relatively unskilled 50 help, and so assembled that the screen may be easily repaired by removing one damaged section and replacing it by a similar interchangeable section, such repairs being susceptible of being made by unskilled help, 55 without the use of special machinery and at

the spot or locality where the screens is being employed. This invention also permits the use of cast iron for the supporting grille thereof, and the accurate machining thereof prior to assembling, and also eliminates 60 many of the small parts which are customarily required for the building up of a screen of this description.

The invention will be best understood by reference to the following description when 65 taken in connection with the accompanying illustration of one specific embodiment thereof, while its scope will be more particularly pointed out in the appended claims.

In the drawings:

Figure 1 is a side elevation, partly in section and partly broken away, showing a paper cylinder mold embodying one form of the invention;

Fig. 2 is a side elevation, partly in end view and partly in section, on the line 2-2 of Fig. 1, showing the same cylinder mold;

Fig. 3 is a plan view of one of the segmental sections of the supporting frame or 80 grille;

Fig. 4 is a side elevation of the same; and

Fig. 5 is a plan view of a portion of the foraminous covering which may be applied to the frame.

Referring to the drawings, and to the embodiment of the invention illustrated therein, the same is constructed of interchangeable sectional parts assembled upon the shaft or spindle 1, the cylindrical frame 90 work being carried by a series of radial supporting members which herein are in the form of spiders. These consist of similar end spiders 2-2 and intermediate spiders 3-8, the latter being of the same construction and of any suitable number, according to the length and number of longitudinal sections desired for the drum.

Besides the segmental supporting sections which unite the adjacent spiders and 100 which are hereinafter more particularly described, the spiders are herein longitudinally united by a series of tie rods 5, each one of which passes through holes in the corresponding legs of successive spiders, 105 there being provided one tie rod for each spider leg, the latter being herein six in number. To assist in spacing the spiders, they are separated (Fig. 1) by the tubular spacing members 6, which latter have the 110

end plugs or blocks 7 resting against the spider legs. The tie rods 5 and spacing tubes add to the rigidity of the structure, but if desired, may be omitted for the sake 5 of simplicity and cheapness, and the segmental units relied upon to unite the several sections in the structure.

Each of the intermediate spiders 3 carries a circumferential ring 8, the periphery of 10 which at 9 is accurately machined to the required diameter of the supporting frame, and opposite faces of which are also machined to receive side walls 10 of the segmental supporting units which go to make 15 up the supporting frame.

These segmental supporting units are preferably similar in construction and interchangeable, the details of one of such units being shown more particularly in Figs. 3 20 and 4. Each segmental unit is in skeleton or open or grille shaped form and consists of the side walls 10, united by the cross webs 11 and the intermediate web 12, together with the segmental arc-shaped supporting 25 members 13. The latter, when assembled, form continuous ring-supporting members intermediate the spider ring-supports 9 and accurately machined to have the circumferential dimensions corresponding to the dimensions of the spider ring supports 9.

These segmental sections 4 may be fastened to the faces of the adjoining spiders by means of clamping bolts 14. If desired, the circumferentially adjoining ends of adjacent sections in the same unit may be secured one to the other. This, however, is not necessary, and herein the segments are bolted only to the spiders, bringing into abutment, or approximate abutment, adjoining 40 ends of the ring-supporting segments 13, as shown in the lower part of Fig. 1.

In order to prevent any unevenness which might be imparted to the foraminous covering applied to this framework due to a longitudinally continuous line of joints between adjoining segments, the joints between the adjoining segmental ring-supports are staggered or thrown out of line by extending, as represented in Fig. 3, one ring-supporting 45 segment 13 to the point 15 farther beyond the web 11 than the end 16 of the remaining ring segment, while at the opposite web extending the last-named ring segment to the point 17 farther than the end 18 of the first 50 named ring segment.

When assembled, the adjacent long and short projections of the ring segments in any one section abut or face respectively against the corresponding short and long projections 55 of the adjacent unit, as indicated in Fig. 1.

Each end spider 2 is also provided with a circumferential ring 19, the inner face of which is machined to receive and have bolted thereto the side walls 10 of one set of segmental sections.

It will be seen that the frame work of this screen or cylinder mold is grille shaped or open in form, presenting to the foraminous covering a series of circumferential ring supports formed by the ring segment 13 and the spider rings 9. The frame further comprises a series of longitudinally united sections, each section consisting of a spider with a set of individual segmental frame units bolted thereto, the units being longitudinally united 70 by bolting the frame units of one section to the spider of the next adjacent section. Furthermore, it will be understood that the various longitudinal sections which go to make up the cylindrical frame are preferably precisely alike, except the end sections where the end spiders differ slightly in construction, so that any one intermediate section may be easily removed and a similar standardized intermediate section substituted 85 therefor, or either end section may be removed and a similar standardized end section substituted.

It will also be observed that the segmental frame units which are continuously and circumferentially united in each section are preferably precisely alike and standardized in form, so that any one segmental unit may be removed and another similar unit substituted in its place. Herein, the circumferential units are eight in number, but more or fewer may be employed as may be desired.

By the described construction, the spiders and the segmental frame units may be made of cast iron, and the circumferential ring supports 13, on which the foraminous covering is to be applied, as well as the side walls 10, may be accurately machined prior to assembling. This machining and the drilling of the holes in both the spiders and the segmental sections may be done individually and prior to assembling with the aid of templets or jigs by automatic machinery, and by relatively cheap, unskilled labor, and the parts thus accurately made in standardized form may be assembled by relatively unskilled labor, thus resulting in a great saving of expense. Furthermore, required repairs may be cheaply and easily made at the mill where the screen or mold is in use, since a standard section or a standard segment may be supplied and substituted at any time for a damaged one, and such repairs may be made by relatively unskilled labor. In addition to these advantages of cheapness and ease of 110 repairs, the described form of screen frame has the further advantages of being stiff, strong, light, true and open.

The frame-work as described may be covered with any desired form of foraminous covering. Herein, I have shown the frame-work covered as with the relatively coarse covering 20, shown in Fig. 5. This may be applied in any desired way, but herein, as indicated in Fig. 2, I have shown this cov- 120

ering as comprising four adjacent segments united longitudinally along elements of the cylinder by means of the angle pieces 21, which are bolted together. This cylinder 5 may be then covered with any of the usual wire or wire mesh coverings, as desired, as for example, the wire covering indicated at 22 and the still finer wire covering indicated at 23.

10 While I have herein shown and described for purposes of illustration one specific embodiment of the invention, it will be understood that extensive deviations may be made therefrom, and from the mechanical details 15 herein shown, and from the relative arrangement of parts, all without departing from the spirit of the invention.

Claims.

1. A screen for paper manufacture having 20 a support for its foraminous covering comprising a series of longitudinally united units, each unit comprising a plurality of segmental frame supporting sections.

2. A screen for paper manufacture having 25 foraminous covering and a cylindrical support for its foraminous covering comprising a shaft, a series of spiders mounted thereon, and a supporting framework carried by the spiders comprising individually separable 30 segmental sections between adjacent spiders forming a circumferentially continuous supporting frame.

3. A screen for paper manufacture having 35 a cylindrical support for its foraminous covering comprising a shaft, a series of spiders mounted thereon, and a supporting framework carried by the spiders comprising a plurality of segmental grille-like sections between adjacent spiders, said sections forming 40 between adjacent spiders a circumferentially continuous supporting frame and presenting one or more accurately dimensioned ring supports to serve as a rest for the foraminous covering.

4. A screen for paper manufacture having 45 a support for its foraminous covering, the same including sets of similar, interchangeable segmental sections, each set presenting one or more ring-like supports formed by 50 the segments of that set and serving as a rest for the foraminous covering, the joints between the segments of successive rings being longitudinally out of line.

5. A screen for paper manufacture having 55 a support for its foraminous covering, the same including sets of similar, interchangeable segmental sections; each set presenting one or more ring-like supports formed by the segments of that set and serving as a rest 60 for the foraminous covering, the joints of one ring being displaced with relation to the joints of another supporting ring whereby the foraminous covering may be applied to the support more evenly.

6. In a screen for paper manufacture, a

support for the foraminous covering comprising a plurality of radial supporting members, each radial support having secured thereto a series of segmental, grille-like frame pieces forming a circumferentially continuous supporting frame for the foraminous covering.

7. In a screen for paper manufacture, a supporting frame for a series of units longitudinally united, each unit comprising a 70 plurality of segmental, grille-like, cast-iron sections having accurately machined supporting surfaces circumferentially united into a substantially continuous supporting frame for the foraminous covering. 80

8. A screen for paper manufacture having a foraminous covering and a support for the foraminous covering built up from end to end of interchangeable sections having individually machined, interchangeable 85 frame supporting segments.

9. A screen having an exterior foraminous covering and a cylindrical, open-work frame support for the covering, said support being formed of circumferentially separated, 90 interchangeable, individually removable, sectional units presenting each exterior, arc-shaped supporting walls providing when assembled a cylindrical supporting frame 95 for the covering.

10. As an article of manufacture, a segmental section for a cylindrical screen consisting of an open, skeleton, grille-like segment portion provided with means for securing the same in appropriate position on 100 a radial support.

11. As a new article of manufacture, a segmental section for a cylindrical screen frame having arc-shaped supporting ring segments connected by cross webs and presenting arc-shaped exterior supporting walls for the foraminous covering of the screen, 105 said walls extending from end to end of the section.

12. As a new article of manufacture, a 110 segmental section for a cylindrical screen frame consisting of an open skeleton, grille-like segment having a plurality of longitudinal webs including one or more arc-shaped, supporting ring segments connected 115 by cross webs.

13. As a new article of manufacture a segmental section for a cylindrical screen frame having a plurality of longitudinal supporting arc-shaped ribs of equal length 120 but circumferentially offset.

14. A screen for paper manufacture having a frame consisting of longitudinally united units, each comprising a radial supporting member and carrying an open cylindrical frame-work having both circumferential and longitudinal uniting ribs. 125

15. A screen for paper manufacture having a frame consisting of longitudinally united units, each comprising a radial sup- 130

porting member and carrying an open cylindrical frame-work, and tie rods tying the radial supporting members together.

16. A screen having a foraminous covering and provided with a supporting frame-work having interchangeable, ring supporting members presenting longitudinally separated, ring supports for said foraminous covering.

17. A screen for paper manufacture having an exterior foraminous covering and an underlying support therefor, the latter comprising a series of supports with means uniting them into a skeleton supporting frame, and interchangeable members carried by said supports and providing a main circumferential support for the foraminous covering whereby said circumferential supporting members may be replaced without dismantling said skeleton support.

18. A screen for paper manufacture having an exterior foraminous covering and an underlying support therefor, the latter comprising a series of radial supports with means uniting them into a skeleton supporting frame, individually machined members carried by said radial supports providing a main support for the foraminous covering, said members being individually removable and replaceable without dismantling said skeleton frame.

19. A screen for paper manufacture hav-

ing an exterior foraminous covering and an underlying support therefor, the latter comprising parts united into a skeleton supporting frame, and interchangeable supporting members carried thereby presenting when assembled separated ring-like supports on which the foraminous covering may be laid and secured.

20. A screen for paper manufacture comprising an exterior foraminous covering, a skeleton supporting frame, and means providing an underlying, circumferential skeleton support for the foraminous covering comprising members individually replaceable and removable from the supporting frame without dismantling the latter.

21. A screen for paper manufacture having an exterior foraminous covering and a support therefor, the latter comprising a series of supports with means for uniting them into a skeleton supporting frame, and interchangeable members carried by said supports comprising each segmental separated units and providing one assembled and main circumferential support for the foraminous covering whereby said units may be replaced without dismantling said skeleton frame.

In testimony whereof, I have signed my name to this specification.

ANTON J. HAUG.
